UNITED STATES PATENT OFFICE.

CHARLES E. KNAPP, OF NEW YORK, N. Y.

POROUS RUG-HOLDER.

No. 922,703.

Specification of Letters Patent.

Patented May 25, 1909.

Application filed January 18, 1906. Serial No. 296,614.

To all whom it may concern:

Be it known that I, CHARLES E. KNAPP, a citizen of the State of New York and United States of America, residing at No. 900 5 Union street, borough of Brooklyn, county of Kings, city and State of New York, have invented a new and useful Improvement in Porous Rug-Holders, of which the following is a specification.

10 It is well known that carpets, rugs, matting and the like when laid loosely on floors are liable to slide along when stepped upon or when a chair or other furniture is moved upon them, and are thus dangerous to life 15 and limb. The object of my invention is to provide an improved holder to be attached to the under side of the rug or the like to keep it from slipping on the floor.

In carrying out my invention I make a triangular corner of flexible material such as 20 rubber having a rough surface vulcanized to a piece of cloth of the same shape but extending outwardly beyond the rubber, and said corner of rubber or other flexible material 25 will cling to a smooth surface or floor preferably by having pores at proper intervals which extend through the rubber to the cloth. This holder can be readily fastened by sewing or affixing by proper devices the 30 projecting cloth edges to the corners of the under side of the rug, carpet or matting, thus making a rough, clinging, solid and neat surface against a smooth floor with sucker-like attributes to the pores, which in a practical way prevents the slipping and sliding 35 above referred to.

Reference is to be had to the accompanying drawings forming part hereof, wherein—

Figure 1 is a face view of the rug holder 40 attached to the corner of the under side of the rug, matting or carpet. Fig. 2 is a face view of the rug holder unattached and Fig. 3 is a cross section thereof.

My improved rug holder A is shown in triangular form adapted to fit at the underside 45 of the corner of a rug or the like B, and the

holder may be made of rubber or other flexible material adapted to cling to a floor or smooth surface, and to assist such clinging said holder is shown provided with pores or 50 holes a. The holder A is fixed to a piece of cloth C, as by vulcanizing them together, and said cloth is shown of the same shape as the holder but of greater area so that it will extend outwardly beyond the holder providing 55 projecting margins or edges D. The holder may be secured to the rug or the like by placing the cloth backing C against the rug and sewing through the margins or edges D and through the rug or the like. As the 60 holder A projects beyond the plane of the edges D of the backing C the stitches or other fastenings passing through the edges D will be kept from contact with the floor and thus prevented from becoming worn and 65 releasing the holder.

Having now described my invention what I claim is:—

A rug holder comprised entirely of but two parts, first a solid rubber base of triangular form having straight unbroken bounding sides, said base being formed with a series of transverse suction perforations which extend through the top and bottom faces thereof, and second a top part formed of cloth material of tri-angular form having straight unbroken bounding sides, said top being vulcanized to said base and having its sides extending beyond the corresponding sides of the base, said cloth extending throughout 75 the area of said rubber to thereby serve as a stiffening means therefor, and to also close the tops of said perforations of the rubber.

In testimony whereof, I have signed my name to this specification in the presence of 80 two subscribing witnesses, this 16th day of January, 1906.

CHARLES E. KNAPP.
